UNITED STATES PATENT OFFICE.

ALFRED F. KRUMHOLZ, OF CHICAGO, ILLINOIS, ASSIGNOR OF ONE-HALF TO AUGUST KRUMHOLZ, OF CHICAGO, ILLINOIS.

FIRE-BOX.

1,271,479.

Specification of Letters Patent.

Patented July 2, 1918.

Application filed April 5, 1918. Serial No. 226,796.

To all whom it may concern:

Be it known that I, ALFRED F. KRUMHOLZ, a citizen of the United States, and resident of Chicago, in the county of Cook and State 5 of Illinois, have invented certain new and useful Improvements in Fire-Boxes, of which the following is a specification.

My invention relates to fire boxes and particularly to means for effectually containing otherwise unburned products of 10 combustion.

In the co-pending application of August Krumholz, Serial No. 208,666, filed December 24, 1917, there is disclosed a device similar to that shown herein, in which a pair of vertically disposed baffles are arranged transversely of the fire box in the front of the flues, the arrangement being such that products of combustion are caused to pass 15 vertically downward between the two baffles or water cooled boxes and be projected into a highly heated zone. One of the objections to this and similar forms of smoke consuming devices is in that when located as 20 shown it is impossible to expose the entrance to the flues in order to clean the same as is required for efficient transfer of heat.

An object of my invention is to so mount a device of this character that the same may 30 readily be displaced from its operative position to permit of cleaning the flues all without the necessity for removing the baffles. The desired result is secured by mounting the baffles on alined pivots the pivots 35 acting as the water connections for the baffles.

One of the novel features of my improvement is that of locating the packed joints within the water cooled boxes. In other 40 words, providing means for surrounding the joint with water to avoid deterioration and burning out. This result is secured by providing recesses in communication with the water spaces, said recesses accommodating 45 the socket in which the enlarged end of the water supply nipples is held by suitable packing in the form of a gland. Preferably the pivotal joint of the baffles is located at a point one side of the center of the baffles, 50 as in this manner the baffles may be located closer to the flues and still permit the water cooled part to be swung to expose the flues.

The invention will be more readily understood by reference to the accompanying 55 drawings, wherein,

Figure 1 is a transverse vertical section through a fire box equipped in accordance with my invention;

Fig. 2 is a longitudinal sectional view taken on the center line of Fig. 1; 60

Fig. 3 is an enlarged sectional view taken on the line 3—3 of Fig. 4, and,

Fig. 4 is a sectional view taken on the line 4—4 of Fig. 3.

In the drawings a fire box is shown as- 65 associated with a boiler having side sheets 10, and crown sheet 11. Flues 12, of the usual form are provided.

Mounted within the fire box and extending transversely thereof are two water 70 cooled baffles 13, 14, vertically arranged and spaced apart. The lower edge of the box 13, is adapted to lie at or below the surface of the fuel bed, the products of combustion arising from the fuel bed being caused to 75 pass upwardly, thence downwardly between the two boxes and into the zone of highest heat where any unconsumed gases are burned. The baffles 13, 14 are inter-connected at four points by means of the pipes 80 15. Stay-bolts 16, will be located at proper points in the box to stiffen the same as required. Preferably the boxes are formed by welding the same when completed being 85 in effect one piece.

In order to expose the ends of the flues to permit of cleaning as required, I prefer to pivot the baffles in such manner as to permit of their being swung 90°. In order to accomplish this result I provide a trans- 90 verse water conduit 17, fixed in the side sheets 10, and having a vertically upwardly projecting nipple 18, located at a point intermediate the ends of the conduit. The nipple is best shown in Figs. 3 and 4, pref- 95 erably has an enlarged or spherical end 19, which is located in a cylindrical socket 20, formed within a recess 21, in communica- 100 tion with the box 13. It will be noted that there is a water space 22, around the socket 100 20, and therefore that the same cannot be burned out or the packing 23, destroyed. A gland nut 24, serves to clamp the ball end 19, in a well known manner.

The pivot and water connection for the 105 upper end of the box is similar. A nipple 25, projects downwardly from the crown sheet 11, in vertical alinement with the nipple 18. It is held in a packed joint 26, which is a duplicate of that just described. The 110

socket 27, is, however, formed in a recess 28, in the box 14. Thus it will be seen that the circulating water is forced to pass through both of the boxes and cannot be 5 trapped at any point therein. In order to close the space between the top of the box 14, and the crown sheet, I provide a plate 28, secured by bolts 29, to the box 14, and bricks or asbestos blocks 30, are cemented in 10 place on top of the box 14, and against the plate 28. It is obvious that the form of the pivotal connection may be varied somewhat and much the same results secured. It is not essential that the precise details of construction be followed either in the form of 15 the baffles or the arrangement of the water supply or circulating connections. Modifications will suggest themselves to those skilled in the art, and such modifications 20 I consider within the scope of my invention.

I claim:

1. In a fire box, the combination with the top and side walls thereof, of a fixed transverse water conduit, and a pair of spaced vertical water cooled baffles supported between the top wall and said conduit with capacity for swinging movement on a vertical pivot, substantially as described.
2. In a fire box, the combination of spaced, water-cooled vertical baffles, the lower edge of one of which is adapted to lie at substantially the height of the fuel bed, said baffles being mounted on alined vertical pivots with capacity for swinging movement to expose the flues, substantially as described.
3. In fuel burning means, the combination of a water-cooled baffle disposed across the fire box in front of the entrance to the flues, said baffle having vertically alined pivots which act as water connections, whereby the baffle is adapted to be swung to expose the flues, substantially as described.

Copies of this patent may be obtained for five cents each, by addressing the "Commissioner of Patents, Washington, D. C."

4. In a fire box, the combination of a pair of spaced vertical water-cooled baffles located transversely of the fire box in front of the entrance to the flues, said boxes being provided with alined water connections 50 adapted to act as pivots on which the boxes may be swung to expose the flues, substantially as described.

5. In a fire box having flues, the combination of a pair of spaced water-cooled baffles 55 disposed across the fire box in front of the flues, a water pipe extending across the fire box below the baffles, said pipe being provided at a point intermediate its ends with a vertical nipple connecting with one of said baffles by a packed joint, and a vertically alined downwardly projecting nipple also connecting with one of said baffles and held in a packed joint, the arrangement being such that the baffles may be swung on said nipples to expose the flues, substantially as described.

6. In a fire box, the combination of a pair of spaced water-cooled baffles having water connections therebetween, alined water supply and discharge connections on which the baffles are held and adapted for pivotal movement, the water supply connection being in one baffle and the water discharge connection being in the other baffle, substantially as described.

7. A smoke consumer, comprising in combination a pair of spaced hollow baffles having communicating connections, each of said baffles being provided with recesses accommodating a socket with a water space therearound, said sockets being in vertical alinement, nipples having ball ends and packing glands for holding the nipples in the sockets, substantially as described.

Signed at Chicago, Ill., this 1st day of April, 1918.

ALFRED F. KRUMHOLZ.
